UNITED STATES PATENT OFFICE.

GEORGE J. CAPEWELL, OF HARTFORD, CONNECTICUT.

BUTTON-FASTENER.

1,180,375.

Specification of Letters Patent. Patented Apr. 25, 1916.

Application filed July 6, 1914. Serial No. 849,023.

To all whom it may concern:

Be it known that I, GEORGE J. CAPEWELL, a citizen of the United States, residing at Hartford, in the county of Hartford and 5 State of Connecticut, have invented a new and Improved Button-Fastener, of which the following is a specification.

My improvement relates more especially to means for securing buttons to various 10 articles, and more especially to clothing and other articles of wearing apparel, and an object of my invention, among others, is to provide a fastening for a button that shall be cheap in construction, that may be 15 readily applied, and that shall be extremely effective as a securing means.

One form of fastening means embodying my invention and in the construction and use of which the objects herein set out, as 20 well as others, may be attained, is illustrated in the accompanying drawings, in which—

Figure 1 is a view in section through my improved fastening, illustrating the manner 25 of holding a button in place. Fig. 2 is a plan view of the button. Fig. 3 is a detail view in elevation of the holding member of my improved fastener. Fig. 4 is a plan view of the same. Fig. 5 is a detail view 30 illustrating the form assumed by the fastener in an initial step in the fastening operation. Fig. 6 is a detail view showing a slightly different form of fastener. Fig. 7 is a view of the fastener as seen in a plane 35 at right angles to the plane of view of Fig. 3.

My improved securing means may be employed for attaching various forms of fasteners to clothing or other articles, and it is 40 especially adapted for buttons of various kinds, stud and socket fasteners, &c., and these have therefore been selected as a convenient means for clearly setting forth the invention.

45 In the accompanying drawings the numeral 10 denotes a button, of any of the usual forms adapted to be engaged within the button hole of a garment, and as embodying my invention this button includes 50 a hub 11 that is hollow to provide a recess for the reception of my improved fastener, said recess being preferably of a greater area at its bottom than at its outer end. In the form of construction herein shown 55 I provide a socket piece 12 fitting within the tapered opening in the hub 11, this

socket piece being closed at its inner end, that is, that end projecting through or located at the face of the button. The recess 13 is formed in this socket piece that is of 60 greater area at its bottom and tapers gradually to the mouth of the recess. This socket piece is provided with a flange 14 as a means of securing it within the hub 11. The button may be formed of any suitable 65 material appropriate for devices of this class, and the socket piece may be formed of metal, whether the button itself be formed of such material or not.

The fastening member embodying a part 70 of my invention consists of a stem provided with a head 15. This stem includes a longer prong 16 and a shorter prong 17 that may be secured to the head in any suitable manner. As herein shown a single 75 piece of metal is folded to provide a cross piece 18, the ends of which are located underneath lips 19 formed on the under surface of the head, the two branches extending from the cross piece forming the prongs 80 16 and 17. The longer prong is provided with an indentation or shoulder forming a shield 20 on the side next to the shorter prong of the fastener, the latter being of such size that it will lie under and be protected by this indented part or shoulder, so that the two prongs will in effect operate as a single prong tapering gradually from the head 15 to the point 21, the shield protecting the point of the shorter member to 90 85 prevent its catching when the prongs are thrust through the material to which the button is to be secured.

The prongs are preferably formed from a piece flat on one side and rounded on the 95 opposite side, the part to constitute the cross piece, being flattened. With this construction, the ends of the prongs are so distorted and wedged into the recess into which they are driven that they will be held therein 100 with a grip sufficient to answer all of the requirements that will be placed upon the structure in its use as a button. This indented portion or shield of the longer prong also serves another function, which 105 function is that of a guide to direct the movement of the shorter prong after it has entered the recess in the button, and as illustrated in Fig. 5 of the drawings.

In operation the button is placed on that 110 face of the material to which it is to be secured and the stem, consisting of the

prongs 16—17, is forced through the material from the opposite side of said material, said prongs entering the recess 13 in the button. The point of the longer prong, 5 striking the bottom of the recess, will be bent laterally and the point of the shorter prong, engaging the shoulder or shield 20, will be forced outwardly or away from the longer prong 16, and into contact with the 10 side of the recess. The two prongs and especially the longer may assume various forms, depending upon conditions, as to the shape of the recess, the relative resilient qualities of the two prongs, &c., until the stem is completely wedged within the recess and securely held against withdrawal therefrom, thus tightly securing the button in place. The construction will, however, give to the 15 prongs the general shape shown in Fig. 1, in which the shorter prong 17 is forced outward against the side wall of the recess and the part of the longer prong forming the shoulder 20 will be bent into a strut serving to hold both the shorter prong and that part 20 of the longer prong below said shoulder, firmly engaging the side walls of the recess.

In Fig. 6 my improved fastener is shown 30 as especially applicable for securing a shoe button 24 in place, which button is also especially adapted for formation therein of the recess within which the prongs 16 and 17 of my improved fastening are received, thus securing the head 26 and button firmly 35 against the material 25 to which the button is to be fastened.

While I have shown and described herein a preferred form of fastening embodying my ideas as disclosed herein, it will be understood that this may be changed to 40 a greater or lesser degree and yet be within the spirit and intent of the invention.

I claim—

1. A button fastener including a head having a socket of larger area at the bottom 45 thereof, and a fastening member having a head and a stem consisting of a plural number of prongs having separable and pointed ends, one of which is provided with means for separating the other therefrom and for directing its movement.

2. A button fastener including a head having a socket of larger area at the bottom thereof, and a fastening member having a head and a stem consisting of a plural number of prongs having separable and pointed ends, each provided with means for separating the other therefrom and for directing the movement of the end of another.

3. A button fastener including a head having a socket of larger area at the bottom thereof, and a fastening member having a head and a stem consisting of a plural number of prongs, one of which has a shoulder

to receive and direct the movement of another.

65

4. A button fastener including a head having a socket of larger area at the bottom thereof, and a fastening member having a head and a stem consisting of a plural number of prongs, one of which has a beveled shoulder to receive and direct the movement of another and the other having its end 70 formed to direct the movement of the one.

5. A button fastener including a head having a socket of larger area at the bottom thereof, and a fastening member having a head and a stem, consisting of a longer and a shorter prong, the longer having a recess to receive and shield the point of the shorter, the edge of said recess being shaped to direct 80 the movement of the shorter prong.

6. A button fastener including a head having a socket of larger area at the bottom thereof, and a fastening member having a head and a stem consisting of a longer and a shorter prong, the longer being bent to form a shoulder to overlie the end of the shorter whereby the movements of each into the recess in the socket is directed.

7. A button fastener including a button 90 having a hole extending through it and wider at one end than at the other, a socket piece separately formed therefrom and placed therein to close said hole, said socket piece having a recess of larger area at its 95 bottom, and a fastening member including a head and prongs projecting therefrom, said prongs having means to direct the ends thereof to wedge them within said recess.

8. A button fastener including a head having a socket, and a fastening member having a head and a stem consisting of a plural number of prongs, having separable and pointed ends, said prongs being provided with means for directing the movement of another and in one opposite direction therefrom.

9. A button fastener including a head having a socket, and a fastening member having a head and a stem consisting of a longer and a shorter prong, the longer prong being provided with means to cause it to be bent and form a strut to hold the shorter prong against the wall of the recess.

10. A button fastener including a head having a socket, and a fastening member having a head and a stem consisting of a plural number of prongs, each of which is provided with means for deflecting the movement of the others thereby causing the prongs to 115 diverge into said socket.

GEORGE J. CAPEWELL.
